UNITED STATES PATENT OFFICE.

GEORGE J. WHEELOCK, OF OAKLAND, ASSIGNOR OF ONE-HALF TO NAPOLEON BEAUREGARD, OF SAN FRANCISCO, CALIFORNIA.

DUMPING-CAR.

SPECIFICATION forming part of Letters Patent No. 290,298, dated December 18, 1883.

Application filed September 28, 1883. (No model.)

To all whom it may concern:

Be it known that I, GEORGE J. WHEELOCK, a citizen of the United States, residing at Oakland, Alameda county, State of California, have invented a new and Improved Dump-Car, of which the following is a specification.

My invention relates to those cars used in mining, grading, and for general excavating purposes, which are required to tip over the box or body, independent of the truck to which the wheels are attached, in the act of discharging the load.

It consists in the combination of machinery by which the dumping is effected, the object being to keep the height of the car within the limit required by the truck-frame and car-body, and not occupy any of the height with the dumping machinery—a desideratum in cases where the car has to enter low-roofed tunnels—and also to obtain a simple, cheap, and effective device for the purpose intended.

In the accompanying drawings, Figure 1 is an end view, and Fig. 2 is a side elevation, 25 of my invention.

In both figures like letters of reference refer to like parts.

A is the car-box, made in ordinary fashion. B is the swinging door at the dumping side, 30 which is fastened with the cross-bar C. This bar C swings on a pivot at D, and each end passes into the latches E, which are fastened on the frame-posts F. The ordinary guides for the bar are fastened on the door itself.

35 G is the truck-frame.

H are the wheels, which turn upon their respective axles, the axles being rigidly held in boxes secured on the under side of the truck.

40 I I are rollers, which are provided with short axles which turn in suitable metal boxes properly secured in position upon the truck-frame, as shown. Upon these rollers the dumping side of the car-body rests, the opposite side resting squarely on the truck-frame, the blocks T being interposed.

45 J J are toothed racks, which are fastened to the car-body underneath at each end. With these racks there engage two cam-shaped

toothed quadrants, K K. The quadrants are 50 secured in proper position upon the square shaft L, which runs the entire length of the truck-frame, about two inches to one side of the center line, or four inches nearer the dumping side than the opposite side. This 55 square shaft is supported in boxes M on the truck-frame, and has two hand-levers, N N, which serve to turn it in operating to dump and return the car-box to its normal position.

O is a chain, which connects the car-box 60 with the truck-frame. Its office is to prevent the car-box from being inclined in dumping the load to a greater distance than the length of this chain will permit.

P P are flat bars attached to underneath the 65 box of the car, and resting on each of the three rollers. At a proper point each bar is provided with a hook-shaped stop, Q, which, when the car-box is moved sufficiently far sideways to be in a position to dump the load, 70 the stop strikes against the rollers and prevents further movement, except in the matter of tipping the car-box over.

The door of the car is suspended on bolts at R.

The car needs no locking device to prevent tipping over or moving sideways when in transit, for inasmuch as the whole body rests fairly on the broad support of the truck-frame and the rollers, there is no tendency to tip 80 over, and before any side movement is possible the car-box, with its load, must be actually lifted to enable it to be rolled on the rollers.

The operation is simple and as follows: 85 The door is closed and made fast when the car is loaded. Afterward, when the car is rolled to its dumping-place, the door-fastening is swung out, to allow the door to open, when the operator, at one or the other end of 90 the car, throws over the hand-lever, which, through the connected machinery, effects the dumping by first raising the car-body just enough to cause the whole weight to come on the rollers and the quadrants, and to lift the 95 wooden stop-blocks T above the truck-frame, and then rolling the car-body over until it loses its balance and tips over to spill out

the contents. The chain will check the car-body from attaining such a position as to fall off from the truck-frame entirely.

What I claim as my invention, and desire to secure by Letters Patent, is as follows:

1. The combination of the racks J, quadrants K, shaft L, and levers N, substantially as and for the purpose herein described.
2. The combination of the rollers I, and

bars P, having cast upon them the hook-shaped stops Q, which fit the periphery of the rollers, so that the car may be tilted with the smooth axles of the rollers for an axis, substantially as and for the purpose described.

GEORGE J. WHEELOCK.
